DRAIN FITTING

Gunnar B. Nystrom, Cleveland, Ohio, assignor to
The Republic Brass Company, Cleveland, Ohio,
a corporation of Ohio

Application October 26, 1938, Serial No. 237,048

1 Claim. (Cl. 4—203)

This invention relates to a plumbing fixture and more particularly to a drain fitting which is particularly adapted for use with a wash bowl or the like.

5 Drain fittings of this character heretofore constructed have the serious disadvantage in that much time and effort are consumed in assembling the unit, it being necessary to disassemble all of the parts in order to secure the unit to a bowl or tub.

One of the objects of this invention is to provide a drain fitting of simple construction and which avoids the difficulties mentioned.

Another object of the invention is to provide a 15 drain fitting of the same general construction which is adapted to be secured in place or removed without any substantial disassembling of parts.

A still further object of the invention is to 20 provide a drain fitting which comprises few parts which are well adapted for quantity production at a minimum cost.

Further and more limited objects of the invention will appear as the description proceeds and by reference to the accompanying drawing in 25 which Fig. 1 is a view partly in section and partly in elevation showing my improved drain fitting connected to a common and well known type of wash bowl; Fig. 2 is a vertical sectional view of the drain fitting showing the drain valve in the 30 open position; and Fig. 3 is a view partly in section and partly in elevation with the parts of the drain fitting partially disassembled in order to show the manner of securing the drain fitting in place.

35 Referring now to the drawing, the reference character 1 designates a washbowl of the usual construction and which has a drain opening 2 therein and which is also provided with an overflow opening 3 which connects with an overflow passageway or bore 4 which is usually formed integral with the bowl in a manner well known to those skilled in the art.

The drain fitting proper consists of a one-piece 40 hollow casting 5 having a straight portion 6 and an angularly disposed portion 7 communicating therewith. The straight portion of the casting is exteriorly threaded to the extreme upper edge thereof. The upper edge of the casting is provided with a valve seat 8 which is interiorly disposed. Fitting within the straight portion of the casting is a valve member 9 which is provided with radially disposed flanges 10 and 11 which serve to guide the valve member in the straight 45 portion 6 of the casting. The valve proper is

indicated by the reference character 12 and when in the open position normally projects above the bottom of the bowl as shown in Fig. 1.

Threadedly secured over the top of the upper end of the drain fitting is a flanged ring member 13 which fits within a countersunk opening 2 provided in the bottom of the bowl, as shown in Fig. 1. The valve 12 is slightly tapered so as to neatly fit the tapered valve seat 8 formed on the upper end of the drain fitting. The outer 5 diameter of the valve 12 is slightly less than the inner diameter of the flanged ring 13 so that the flanged ring may be readily removed from the upper end of the fitting. The lower end of the valve member is provided with an eye 14. Piv- 10 otally mounted in the angular portion of the casting is a valve operating lever 15 which is provided with a spherical portion 16. Fitting within the angular portion 7 is a fiber washer or bushing 17 against which the spherical portion 16 of the 15 valve operating lever bears. The valve operating lever is held in place by a threaded cap 18 which receives therein a coil spring 19 which serves to urge the valve operating lever toward the left as seen in Fig. 2 and to provide for a snap action 20 movement of the valve. Connected with the outer end of the valve operating lever 15 is a 25 lever 20 which is pivotally secured at its lower end and extends through an opening 21 provided in the overhanging portion of the bowl. It is 30 of course to be understood that suitable connections are provided for delivering water to the bowl, which forms no part of this invention.

The upper end of the drain fitting is provided with a pair of openings 22 which communicate 35 with the overflow passageway 4 so that the overflow from the bowl may escape through the drain fitting. Threadedly secured to the lower end of the fitting is a drain pipe 23. Secured over the upper end of the fitting is a rubber washer 24, a metal washer 25 and a nut 26. In order to secure the drain fitting in place, it is merely necessary to remove the flanged ring 13 and to insert the upper end of the fitting through the drain opening 2 and to then threadedly engage the flanged 40 ring 13 with the upper end of the fitting. The washers 24 and 25 are then moved to the positions shown in Fig. 1 and the nut 26 tightened to securely fasten the fitting in place. When it is desired to remove the fitting, it is merely necessary to loosen the nut 26 and to push upwardly 45 on the fitting until the flanged ring 13 is accessible so that it may be removed. The entire fitting may then be removed through the drain opening without disassembling any parts. 50

In fittings of this character heretofore used, it has been necessary to entirely disassemble the unit and to remove the valve and its operating mechanism as well as the nut and washers and to then re-assemble the parts in order to secure the fitting in place. With my improved construction it will be seen that the drain fitting may be quickly secured in place or removed with a minimum effort thereby effecting a considerable saving in the time and labor required. It will also be seen that the nut 26 and the detachable flanged ring 13 cooperate to provide means for effectively securing the fitting in place and that the drain fitting, aside from the valve and its operating mechanism, consists of only two parts which are well adapted for quantity production at very low cost.

It will now be clear that I have provided a drain fitting which will accomplish the objects of the invention as hereinbefore stated. It is of course to be understood that the form of the invention herein disclosed is merely illustrative and is not to be considered in a limiting sense as various changes may be made in the details of construction without departing from the spirit of my invention. The invention is therefore limited

only in accordance with the scope of the appended claim.

Having thus described my invention, what I claim is:

The combination of a bowl having a drain opening and an overflow opening, a drain fitting detachably secured in said drain opening and being exteriorly threaded to the extreme upper edge thereof, a flanged ring threadedly secured over the upper end of said fitting and normally disposed flush with the bottom of said bowl, a poppet valve slidably mounted in said fitting, said flanged ring having an opening therein larger than said valve whereby to permit the valve to pass therethrough, a valve seat formed on the upper end of said fitting and interiorly thereof, said fitting having a plurality of overflow openings therein disposed below and immediately adjacent said flanged ring and said bowl having an overflow passageway connected with said overflow openings, a nut threadedly secured over said fitting and cooperating with said flanged ring to secure said fitting in place, and mechanism for operating said valve.

GUNNAR B. NYSTROM. 25
